EXPANSIBLE BIT

John C. Stokes, Houston, Tex., assignor to Reed
Roller Bit Company, Houston, Tex., a corpora-
tion of Texas

Application June 20, 1936, Serial No. 86,247

18 Claims. (Cl. 255—75)

This application relates in general to a rotary underreamer or expandable bit, and has particular reference to a means for moving the blades to and from operative position.

5 It is one object of this invention to provide an underreamer or expandable bit which will be relatively inexpensive to construct and simple and sure in its operation.

It is an object of this invention to provide 10 an underreamer, the blades of which will be expanded to operative position, and then contracted to inoperative position, both the expansion and contraction being effected by means of fluid pressure exerted through the drill stem.

15 It is a further object to provide a means for expanding and contracting the blades of an underreamer in which no mechanical connection is required with the top of the well other than the customary hollow drill stem to which the underreamer is attached.

20 It is a further object to provide a means for expanding and contracting the blades of an underreamer by fluid pressure exerted through the drill stem without preventing the circulation of 25 washing fluid through the drill stem either during or before the operation of the underreamer.

It is a further object to provide a means for 30 expanding and contracting the blades of an underreamer in which both operations are accomplished by downward pressure on the fluid within the drill stem, but in which no retraction of 35 the blades will occur until it is desired by the operator.

With the foregoing and other objects in view, 35 this invention is constituted of the various parts and combinations set forth in the accompanying drawing, and the following description, it being understood, however, that such disclosure is by way of illustration and example only, and 40 is not to be taken as in any way limiting the spirit or scope of this invention. Such limitation is to be only by the prior art and by the terms of the appended claims.

Referring now more particularly to the drawing 45 in which like numerals indicate corresponding parts throughout:

Fig. 1 is a view partly in elevation and partly in vertical cross section illustrating an underreamer constructed in accordance with this invention with the blades thereof in expanded or 50 operative position.

Fig. 2 is a view similar to Fig. 1, illustrating 55 the same structure after the blades have been expanded and then retracted.

Fig. 3 is a bottom plan view of the structure as illustrated in Fig. 1.

Referring to Fig. 1 of the drawing, the numeral 1 indicates a fitting secured to the lower end of the drill stem, and having a reduced externally threaded part 2 at its lower end adapted to threaded receive the upper end 3 of the coupling member 4. The lower end of this coupling member is similarly reduced and externally threaded at 5 to receive the upper internally threaded end 6 of the barrel or bit head 7. Secured within the lower end of the coupling 4 is a ring 8 which may be welded as at 9, or otherwise suitably secured in place, and upon the upper face of which is formed a seat 10 for a 15 purpose to be presently set forth.

Within the upper end of the barrel 7 there is formed a cylinder 11, the lower end of which is defined by an annular shoulder 12 extending inwardly from the wall of the barrel 7. Below 20 this shoulder member there is a second space 13 within the barrel which may likewise be of cylindrical or other suitable form. The lower end of the barrel 7 is formed with oppositely disposed downward projections 14 adapted to 25 embrace the blades of the reamer in the manner to be presently disclosed. The walls of this barrel 7 are further provided with passageways 15 extending from a position adjacent the upper 30 end of the barrel to the lower end of the barrel and opening at the bottom thereof in positions just ahead of the reamer blades.

Within the barrel 7 and extending past the annular shoulder 12 and the ring 8 is a tubular member 16. Mounted on this tubular member 16 at such a position as to permit upward and downward sliding movement within the cylinder 11 is an annular piston 17 secured to the tubular member 16 by welding 18 or the like. This piston is provided with piston rings 19 or other suitable 40 packing.

At its lower end, this tubular member is provided with a plug 20 welded or otherwise secured in place at 21 to close the bore of the tube, and with a nut 22 threaded on the exterior of the 45 tube 16. This nut 22 carries a pair of downwardly extending ears or lugs 23 which in turn receive the transversely extending pin 24 which is threaded into one of the lugs 23 and latched in place by means of a cotter key 25 or the like. 50 This pin 24 is adapted to extend through slots 26 in the reamer blades 27 in the manner illustrated in Figs. 1 and 2, and thus to form a means for supporting and for positioning these blades. The barrel 7 is formed adjacent its lower end with 55

an internal groove 28 adapted to cooperate with the lugs 29 and lugs 30 on the reamer blades 27 so as to properly position these blades in their extended and retracted positions, respectively.

5 The lower end of the barrel 7 is furthermore provided with a pair of slots 31 and 32 for the purpose of assembly to make it possible for the upper portions of the blades to be passed upwardly to a position within the barrel as they are illustrated in Figs. 1 and 2. These slots are necessary because the upper ends of these blades are too large to pass into the barrel otherwise.

10 The upper end of the tubing 16 is closed by means of a plug member 33 welded or otherwise suitably secured in place, and is normally surrounded by a ring 34 held against longitudinal movement with respect to the tubing by means of a shear pin 35. This ring 34 carries a valve member 36 which may be in the form of a leather washer or the like adapted when moved downwardly to seat against the seat 10 on the ring 8. Above this valve member the ring 34 is threaded to receive the lower end 37 of a second tubular member 38. This member 38 has openings 39 therein so that the fluid may freely pass into the tubular member, and is closed at its upper end by means of a plug 40 which may be welded into position. The tubular member 16 is provided with lateral openings 41 which are normally closed 20 by the ring 34 when it is in the position illustrated in Fig. 1. This tubular member is also provided with a second opening 42 just below the annular piston 17. It is to be noted that the shoulder 12 is spaced slightly from the wall of the tubing 16 as illustrated at 43.

15 The operation of the device just described is as follows:

25 As the device is lowered into the well, the blades and the tubular member 16 occupy their retracted positions as illustrated in Fig. 2. When the device is being lowered, however, the ring 34 and the tubular member 38 are retained in their upper position by means of the shear pin 35. Upon reaching the lower end of the pipe below 30 which the reaming is to be done, fluid is pumped down through the drill stem and serves to force the piston 17 downwardly and expand the blades 27 until the parts occupy the position illustrated in Fig. 1. During this downward movement of 35 the piston, the fluid therebelow will be allowed to drain out through the space 43. In this position, it will be seen that the fluid may still pass down through the drill stem, and that the drilling may take place with washing fluid supplied to the 40 blades 27 through the medium of the passageways 18.

45 When the drilling is completed, and it is desired to retract the blades and withdraw the reamer, a weight or "go-devil" 44 is dropped into the drill stem and allowed to come in contact with the upper end 40 of the tubular member 38, thus rupturing the shear pin 35 and moving the tubular member 38 to the position illustrated in Fig. 2. In this position, the valve member 36 50 seats against the seat 10 on the ring 8 and prevents further flow of fluid downwardly through the drill stem from impinging upon or influencing the piston 17 from the upper side thereof. At the same time, it moves the tubular member 38 to such 55 a position that fluid may enter through the openings 39 and 41 into the tubular member 16. Thence it passes through the opening 42 to a position below the piston 17 and re-acting against the shoulder 12 serves to move the piston 17 in 60 an upward direction and retract the blades 27.

During the raising of the piston some fluid will of course escape through the space 43, but it is contemplated that a sufficient flow of fluid will be obtained to more than overcome this leakage and thus cause upward movement of the piston. 5 After the blades have been retracted, the parts occupy the positions illustrated in Fig. 2 and the reamer may readily be removed from the well.

10 It will be seen from the foregoing that a means has been set forth for accomplishing all of the objects of this invention. It is particularly noted that both the expanding and retracting movement of the reamer blades is accomplished by pumping downwardly through the drill stem, and that the retracting movement cannot be caused 15 by pumping downwardly until it is desired by the operator. It is further noted that during the time that the blades are expanded, washing may continue so that the drilling may properly proceed. 20

Having described my invention, I claim:

1. In an expandible drill, a drill head having a passageway therethrough, a plunger in said passageway, cutter blades at the lower end of said head and adapted to be moved into operative 25 position by downward movement of said plunger, a piston on said plunger slidable within said passageway and adapted to be moved downwardly by downward circulation of fluid through said passageway, means releasably secured in position 30 to initially prevent downwardly circulating fluid from acting upon the lower face of said piston, and means for releasing and moving said releasably secured means to permit downwardly 35 circulating fluid to act on the lower face of said piston and to prevent such fluid from acting upon the upper face of said piston.

2. In an expandible drill, a drill head having a passageway therethrough, a plunger in said passageway, cutter blades at the lower end of said head and adapted to be moved into operative 40 position by downward movement of said plunger, a piston on said plunger slidable within said passageway and adapted to be moved downwardly by downward circulation of fluid through said 45 passageway, means releasably secured to said plunger in position to initially prevent downwardly circulating fluid from acting upon the lower face of said piston, and means for releasing and moving said releasably secured means to permit 50 downwardly circulating fluid to act on the lower face of said piston and to prevent such fluid from acting upon the upper face of said piston.

3. In an expandible drill, a drill head having a passageway therethrough, a plunger in said passageway, cutter blades at the lower end of said head and adapted to be moved into operative 55 position by downward movement of said plunger, a piston on said plunger slidable within said passageway and adapted to be moved downwardly by circulation of fluid through said passageway, said plunger being hollow with openings 60 above and below said piston to permit passage of fluid therethrough to act on the lower side of said piston, means releasably secured in position 65 to prevent such passage and movable on release to permit such passage and to prevent fluid from acting upon the upper face of said piston, and means for moving said releasably secured means.

4. In an expandible drill, a drill head having a 70 passageway therethrough, a plunger in said passageway, cutter blades at the lower end of said head and adapted to be moved into operative position by downward movement of said plunger, a piston on said plunger slidable within said pas- 75

- sageway and adapted to be moved downwardly by downward circulation of fluid through said passageway, said plunger being hollow and having openings above and below said piston to permit passage of fluid therethrough to act on the lower side of said piston, an annular abutment extending inwardly from the wall of said passageway through said drill head to take the reaction when said fluid is acting on the lower surface of said piston, means releasably secured in position to prevent passage of fluid through said hollow plunger and movable on release to permit such passage and to prevent fluid from acting on the upper face of said piston, and means for releasing fluid from the space between said piston and said annular abutment when said piston is being moved downwardly.
5. In an expandible drill, a drill head having a passageway therethrough, a plunger in said passageway, cutter blades at the lower end of said head and adapted to be moved into operative position by downward movement of said plunger, a piston on said plunger slidable within said passageway and adapted to be moved downwardly by downward circulation of fluid through said passageway, said plunger being hollow and having openings above and below said piston to permit passage of fluid therethrough to act on the lower side of said piston, a seat in said passageway above said piston, a collar slidable on said plunger and capable of closing the upper openings in said plunger when in one position thereon and of seating against said seat to close said passageway below said openings when moved from such position, and means releasably holding said collar in said first named position.
6. In an expandible drill, a drill head having a passageway therethrough, a plunger in said passageway, cutter blades at the lower end of said head and adapted to be moved into operative position by downward movement of said plunger, a piston on said plunger slidable within said passageway and adapted to be moved downwardly by downward circulation of fluid through said passageway, said plunger being hollow and having openings above and below said piston to permit passage of fluid therethrough to act on the lower side of said piston, a seat in said passageway above said piston, a collar slidable on said plunger and capable of closing the upper openings in said plunger when in one position thereon and of seating against said seat to close said passageway below said openings when moved from such position, a shear pin for holding said collar in said first named position, means on said collar adapted to receive a weight, and a weight adapted to be dropped against said means to shear said pin and move the collar against the seat in said passageway.
7. In an expandible drill, a drill head having a passageway therethrough, a plunger in said passageway, cutter blades at the lower end of said head and adapted to be moved into operative position by downward movement of said plunger, a piston on said plunger slidable within said passageway and adapted to be moved downwardly by downward circulation of fluid through said passageway, said plunger being hollow and having openings above and below said piston to permit passage of fluid therethrough to act on the lower side of said piston, a seat in said passageway above said piston, a collar slidable on said plunger and capable of closing the upper openings in said plunger when in one position thereon and of seating against said seat to close said passageway below said openings when moved from such position, and means for releasably holding said collar in said first named position.
8. In an expandible drill, a drill head having a passageway therethrough, a plunger in said passageway, cutter blades at the lower end of said head and adapted to be moved into operative position by downward movement of said plunger, a piston on said plunger slidable within said passageway and adapted to be moved downwardly by downward circulation of fluid through said passageway, said head having its walls formed with other internal passageways leading from within said first passageway at a position above the uppermost position of said piston to the lower end of said head, means releasably secured in position to initially prevent downwardly circulating fluid from acting upon the lower face of said piston, and means for releasing and moving said releasably secured means to permit downwardly circulating fluid to act on the lower face of said piston and to prevent such fluid from acting upon the upper face of said piston.
9. In an expandible drill, a drill head having a passageway therethrough, a plunger in said passageway, cutter blades at the lower end of said head and adapted to be moved into operative position by downward movement of said plunger, a piston on said plunger slidable within said passageway and adapted to be moved downwardly by downward circulation of fluid through said passageway, said head having its walls formed with other internal passageways leading from said first passageway at a position above the uppermost position of said piston and terminating at the lower end of said head, means releasably secured in position to initially prevent downwardly circulating fluid from acting upon the lower face of said piston and means for releasing and moving said releasably secured means to permit downwardly circulating fluid to act on the lower face of said piston and to shut off such fluid from the upper face of said piston and from the entrance to said other passageways.
10. In an expandible drill, a drill head having a passageway therethrough, a plunger in said passageway, cutter blades at the lower end of said head and adapted to be moved into operative position by downward movement of said plunger, a piston on said plunger slidable within said passageway and adapted to be moved downwardly by downward circulation of fluid through said passageway, said plunger being hollow and having openings above and below said piston to permit passage of fluid therethrough to act on the lower side of said piston, a seat in said passageway above said piston, said head having its walls formed with other internal passageways leading from said first passageway at a position below said seat and above the uppermost position of said piston and opening at the lower end of said head, a collar slidable on said plunger and capable of closing the upper openings in said plunger when in one position thereon and of seating against said seat to close said passageway below said openings when moved from such position, and means for releasably holding said collar in said first named position.
11. In an expandible drill, a drill head having a

- passageway therethrough, a plunger in said passageway, cutter blades carried by the lower end of said plunger and adapted to be moved into operative position by downward movement of said plunger and out of operative position by upward movement thereof, a piston on said plunger slideable within said passageway and adapted to be moved downwardly by downward circulation of fluid through said passageway, means releasably secured in position to initially prevent downwardly circulating fluid from acting upon the lower face of said piston and means for releasing and moving said releasably secured means to permit downwardly circulating fluid to act on the lower face of said piston and to prevent such fluid from acting upon the upper face of said piston.
12. In an expandible bit, a drill head having a passageway therethrough, a plunger in said passageway, cutter blades carried by the lower end of said plunger and adapted to be moved into operative position by downward movement of said plunger and out of operative position by upward movement thereof, a piston on said plunger slideable within said passageway and adapted to be moved downwardly by downward circulation of fluid through said passageway, said plunger being hollow and having openings above and below said piston to permit passage of fluid therethrough to act on the lower side of said piston, a seat in said passageway above said piston, a collar slideable on said plunger and capable of closing the upper openings in said plunger when in one position thereon, and of seating against said seat to close said passageway below said openings when moved from such position, a shear pin for releasably holding said collar in said first named position, a perforated tubular member on said collar, said member projecting above said plunger and being closed at its upper end and adapted to receive a weight, and a weight adapted to be dropped against said tubular member to shear said pin and move the collar against the seat in said passageway.
13. In an expandible bit, a drill stem, blades adjacent the lower end of said drill stem, means in and operable by downward pressure within said drill stem for expanding said blades, and means controlling said first means and operable to cause such downward pressure to retract said blades.
14. In an expandible bit, a drill stem, blades adjacent the lower end of said drill stem, means in and operable by downward pressure within said drill stem for expanding said blades, and means controlling said first means and shiftable at the will of the operator to cause such downward pressure to retract said blades.
15. In an expandible bit, a drill stem, blades adjacent the lower end of said drill stem, means in and operable by initial downward pressure within said drill stem for expanding said blades, and means controlling said first means and operable to cause subsequent downward pressure to retract said first means to its initial position.
16. In an expandible bit, a drill stem, blades adjacent the lower end of said drill stem, means in said drill stem carrying said blades and operable by initial downward pressure within said drill stem for expanding said blades, and means controlling said first means and operable to cause subsequent downward pressure to retract said first means to its initial position.
17. In an expandible bit, a drill stem, blades adjacent the lower end of said drill stem, means on said drill stem carrying said blades and operable by initial downward pressure within said drill stem for expanding said blades, and means controlling said first means and operable to cause subsequent downward pressure to retract said blades to their initial position.
18. In an expandible bit, a drill stem, blades adjacent the lower end of said drill stem, means in said drill stem carrying said blades and operable by initial downward pressure within said drill stem for expanding said blades and means controlling said first means and operable to cause subsequent downward pressure to retract said first means to its initial position, said drill stem having passageways for conducting washing fluid to said blades, and said last mentioned means being operable to stop flow of washing fluid through such passageways when operated to cause downward pressure to retract said first means to its initial position.

JOHN C. STOKES.
